Attorney

UNITED STATES PATENT OFFICE.

MICHAEL HURLEY, OF ONEONTA, NEW YORK.

HUB-LINER.

1,238,676.

Specification of Letters Patent. Patented Aug. 28, 1917.

Application filed May 3, 1917. Serial No. 166,202.

To all whom it may concern:

Be it known that I, MICHAEL HURLEY, a citizen of the United States, and resident of Oneonta, in the county of Otsego and State of New York, have invented certain new and useful Improvements in Hub-Liners, of which the following is a specification.

The present invention has reference, generally to railway rolling stock and the invention relates more particularly to an improved hub liner.

The invention has for its dominant object to provide a hub liner for driving wheels of locomotives whereby lateral play of the drive wheels will be eliminated, thus overcoming liability of derailment and other dangers incident to such conditions.

Another object of the invention is to provide a hub liner so constructed as to allow the quick arranging of the same upon the drive wheel receiving axle or axles of the locomotive without the necessity of an extensive or special equipment of tools.

It is also an object of the invention to provide a hub liner capable of adjustment in order that the same can be used upon hubs varying in size.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings wherein is shown one of various possible embodiments of my invention;

Figure 1 is a vertical section through the improved hub liner applied bearing block of a locomotive truck,

Fig. 2 is a side elevation thereof partly in section; and,

Fig. 3 an end elevation of the same.

Similar reference characters refer to similar parts throughout the several views of the drawings.

Certain features and aims of this invention will be more readily understood if the following facts be borne in mind: The bearing blocks of locomotive trucks, after a short period of use are worn to such an extent by the locomotive drive wheels as to permit the development of lateral play or

sway of the wheels thereby rendering the same exceedingly dangerous if used thereafter, due to the liability of derailment of the locomotive and the weakening of the axle by reason of the abnormal stress imparted thereto by the wobbling or swaying driving wheels. The above are among the dominant aims of this invention, and are, among others, attained in the constructions of the nature of that hereinafter described.

Referring now more specifically to the drawings, the improved hub liner may be stated to comprise a plurality of sections designated 1 and 2 having marginal flanges 3 and 4 formed upon certain of their sides, portions of the said flanges being extended laterally to provide apertured lugs 5 through which connecting bolts 6 are passed in order that the several sections may be securely united. Corresponding semi-circular recesses 7 are formed within the adjacent portions of the sections 1 and 2 and are of a size to snugly engage the axle "A" of the locomotive truck upon which driving wheels "W" are mounted at either end.

Bearing blocks "H" are carried by the opposite sides of the locomotive truck and are adapted to have arranged over their outer ends the flanged sections 1 and 2, it being understood that the said sections are fixedly engaged therewith through the medium of the connecting bolt 6 passing through the apertured lugs 5. To lock the bolts, suitable nuts are turned into engagement with the screw-threaded extremities thereof and are prevented from having undue movement by passing cotter pins or the like through said screw-threaded extremities.

Within the flanged outer sides of the section 1 and 2 notches or recesses 8 are formed and serve as means for permitting the pins which hold the usual grease cups in the bearing "H" to be removed or replaced without interfering with the operation or positioning of the hub liner in any way.

From the foregoing, it will be understood by workers in the art that with my improved hub liner, the existence of play or lateral movement between the bearing blocks of locomotive trucks and the adjacent drive wheels will be eliminated and further, the hub liner, due to the provision of the connecting bolts 6 may be readily arranged upon bearings varying in size. Further, it will be understood that the liner may be

arranged upon a bearing and a locomotive truck respectively without an extensive or special equipment of tools and will obviate the necessity of welding and fitting the same 5 to the bearing either by hand or by the use of the conventional ox-acetylene welding process.

If it be desired the sections 1 and 2, can be formed of different thicknesses depend- 10 ent upon the play or space existing between the hub and its adjacent driving wheel.

Manifestly, the construction shown is capable of considerable modification and such modification as is within the scope of my 15 claims I consider within the spirit of my invention.

I claim:

1. A hub liner including a plurality of sections having corresponding recesses 20 formed in their adjacent portions, and means passing through said sections for adjustably connecting and clamping the same to a bearing block of a locomotive truck.

2. A hub liner including a plurality 25 of sections having corresponding recesses formed in their adjacent portions, apertured lugs formed upon the outer corners of said sections and projecting laterally there-

from, and bolts passing through the aper- 30 tured lugs for adjustably connecting and fastening the sections to a bearing block of a locomotive truck.

3. A hub liner including a plurality of sections having corresponding recesses 35 formed in their adjacent portions, flanges formed upon the outer sides of the sections having laterally extending apertured lugs projecting therefrom, and bolts receivable through the apertured lugs for adjustably connecting and clamping the sections to a 40 bearing block of a locomotive truck.

4. A hub liner including a plurality of sections having corresponding recesses 45 formed in their adjacent portions, marginal flanges formed upon the outer sides of said sections and having laterally extending apertured lugs projecting therefrom at points, said flanges also having recesses also formed therein, and bolts receivable through the apertured lugs for adjustably receiving 50 and clamping the sections to a bearing block of a locomotive truck.

In testimony whereof, I affix my signature hereto.

MICHAEL HURLEY.

Copies of this patent may be obtained for five cents each, by addressing the "Commissioner of Patents, Washington, D. C."
